193,496

HANDLE OR SIMILAR ARTICLE

Sydney Jacoff, Great Neck, N.Y., assignor to Great Neck
Saw Manufacturers Inc., Mineola, N.Y., a corporation of New York

Filed Oct. 24, 1961, Ser. No. 67,235

Term of patent 14 years

(Cl. D93—4)

FIG. 1 is a perspective view of the handle or similar article showing my new design.

FIG. 2 is an elevational view taken from one side thereof.

FIG. 3 is a top plan view thereof.

FIG. 4 is an elevational view thereof taken from the side opposite that shown in FIG. 2.

FIG. 5 is a bottom plan view thereof.

FIG. 6 is a front elevational view thereof.

FIG. 7 is a rear elevational view thereof.

I claim:

The ornamental design for a handle or similar article, substantially as shown.
